DRINK DISPENSER CASING

Donald S. Reynolds and Robert J. Thorn, Chicago, Ill.

Application November 25, 1955, Serial No. 39,051

Term of patent 14 years

(Cl. D52—3)

The figure is a perspective view of a drink dispenser casing showing our new design.

The characteristic features of our design reside in the portion shown in solid lines in the drawing. The side opposite to that shown and the top are plain.

We claim:

The ornamental design for a drink dispenser casing, as shown and described.
